UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO; ILLINOIS, A CORPORATION OF ILLINOIS.

STAND LAMP.

Application filed January 16, 1920. Serial No. 351,804.

To all whom it may concern:

Be it known that I, REUBEN B. BENJAMIN, a citizen of the United States, residing at Chicago, in the county of Cook and State 5 of Illinois, have invented new and useful Improvements in Stand Lamps, of which the following is a full, clear, concise, and exact description, reference being had to the accompanying drawing, forming a part of 10 this specification.

My invention relates to stand lamps, and more particularly to a cluster type stand lamp.

One object of my invention is to provide 15 a stand lamp wherein an improved light distribution is obtained.

Another object of this invention is to provide a stand lamp wherein the switch mechanism, contacts and binding terminals are enclosed 20 within an ornamental casing thereby providing a neat and compact arrangement of parts.

Another object is to provide a stand lamp comprising an inverted translucent bowl 25 having an electric light bulb therein whereby a diffused light may be obtained when desired.

Another object of this invention is to provide an improved construction whereby different lighting effects may be obtained. 30

Other objects will appear in the detailed description to follow and from the appended claims.

In the drawings—

Fig. 1 is a perspective view of the stand lamp showing a portion of the shade or translucent bowl cut away;

Fig. 2 is a vertical sectional view of the stand lamp with the bowl and shade removed;

Fig. 3 is a plan view of my device with the lamp shade, bowl and ornamental casing removed;

Fig. 4 is a plan view of my device with additional parts removed;

Fig. 5 is a sectional detail taken on the line 5—5 of Fig. 2; and

Fig. 6 is a sectional detail taken on the line 6—6 of Fig. 3.

In order to give a general idea of the invention, it is here stated that the construction shown comprises a lamp pedestal 10 upon which is disposed a metal base supporting member 11 which supports an insulating base 12. Secured to the insulating 55

base 12 is a conducting and supporting member 13, preferably a sheet metal stamping, which has disposed therein a plurality of shell receptacle contact members 14 upon which members 14 are threaded insulating 60 bushings 15.

An ornamental casing 16 surrounds the metal base member 11 and the insulating base 12. This casing is divided, the lower portion thereof being clamped between the 65 pedestal 10 and the metal base member 11. The upper portion of said casing is apertured to receive the insulating bushings 15 which bushings hold the upper portion of the casing in place.

Securely held between one of said bushings 15 and the ornamental casing 16 at one of the apertures therein, as shown at 17, is a bowl supporting member 18 in which is disposed an inverted translucent bowl 19. Supported on said bowl by means of a plurality of clip members 20 is a suitable lamp shade 21.

To give a more detailed description of my construction, the pedestal 10 has an axial opening 22 therein, in which opening is disposed a pipe 23. This pipe 23 is threaded into the metal base 11, as shown at 24, thereby securely holding the base member 11 on the pedestal 10. Suitable conductors 25 and 26 pass up through said pipe 23, conical recess 27 and into a recess 28 in the insulating base 12. The conductors are, therefore, due to said conical recess 27 and said recess 28 given ample space in which they may be supported and secured to their respective binding terminals and also to prevent short circuiting of the conductors.

The lower portion of the ornamental casing 16 has an inwardly extending flange 29 thereon which is clamped between the pedestal 10 and the metal base member 11. Said casing also has an upwardly extending annular flange 30 formed integral therewith within which said insulating base rests to 95 position same on said metal base member.

The insulating base 12 has the cylindrical recess 28 extending from its lower face through which the conductors 25 and 26 pass. An arcuate slot or recess 31 extends also from said lower face of the insulating base 12 and has disposed therein the conductor bars 32 and 33.

The metal stamping conducting member 13 has a plurality of horizontally disposed 100

flange portions 34 thereon through which portions pass the screws 35 thereby securing said member 13 to the insulating base 12 (Figs 2 and 5). The conducting member 13 has three radially extending portions which slope downwardly at 36 and terminate in said flange portions 34. These downwardly sloping portions are apertured and have secured thereto at each opening 10 therein one of the threaded shell receptacle contacts 14. A fourth shell receptacle contact is disposed in a vertical axial plane on said conducting member in the same manner as the shell contacts on the sloping portions.

The switch mechanisms in this construction is of the pull chain type which are suitably disposed in recesses therefor in the insulating base 12. The switch mechanism 20 herein, however, forms no part of the invention.

The switches being identical, description of one will suffice. The switch mechanism comprises a brush carrier 37 which is 25 mounted on and is rotatable with a switch shaft 38 which shaft is rotatably mounted at one end in a slot 39 therefor in the insulating base and is rotatable at its other end in an upwardly extending portion 40 30 which is formed integral with a binding plate 41 (Fig. 5). A brush member 42 is carried by said brush carrier 37 which has connected therewith an arm 43 which engages said upwardly extending arm 40 and 35 the switch shaft 38 thereby electrically connecting the binding plate 41 and the brush 42. A disk or barrier 44 is also mounted on the switch shaft 38 to which is secured a chain rail 45 upon which is mounted a pull chain 46. The chain rail 45 has a hook member 47 formed integral therewith which engages one of the balls of the pull chain whereby the chain is secured to the chain rail. The insulating base 12 and the 45 metal base member 11 are recessed at 48 to allow a passage for the downwardly extending portion of the pull chain in which recess is disposed an eyelet 49. The pull chain has disposed between two balls thereof a 50 cup-shaped stamping 50 which is tapered to enter the eyelet 49. Said cup-shaped member 50 is slightly larger than the opening in said eyelet and therefore cannot pass therethrough but will act as a stop for the pull 55 chain to limit the travel of the brush carrier. A projection 51 (Fig. 6) on the insulating base also limits the travel of the brush carrier by being engaged by the hook member 47 on the chain rail.

60 The switches are electrically connected by means of the conductors 25, 32 and 33, the two latter of which are supported in the slot 31 in the insulating base by means of a plurality of conducting screws 53, 53^a and 65 53^b.

The current to the threaded shell contacts 14 is supplied through the conducting member 13 which has electrically connected thereto by means of a binding screw 54 the conductor 26, as shown at 55 (Figs. 3 and 5). 70

The insulating base 12 has a raised or head portion 56 substantially centrally thereof which has an annular sloping portion 57 extending downward a short distance from the upper surface thereof. A 75 plurality of center contacts 58, 59, 60 and 61 are suitably secured on the head portion of said insulating base, said center contacts being disposed radially with respect to the shell contacts 14 for engagement with the 80 contact portion of any suitable translating device threaded into said shell contacts.

The center contact 58 is a portion of a single piece of metal, preferably spring steel or other conducting material and is formed 85 into hooked portions at each end, one of which constitutes the center contact, the other end constituting a spring contact finger 59 which engages the insulated portion of the brush carrier when the switch is in 90 "off" position as shown in Fig. 2, or engages the brush 38 when the switch is in "on" position. A screw 62 secures said center contact 58 on the insulated base. An insulated block 63 is disposed between the 95 hook portion of the center contact 58 and acts as a support for said contact when the contact portion of a translating device engages the same.

The center contacts 59 and 60 are electrically connected by means of a conducting bar 64, said bar and center contacts being secured on the upper surface of said insulated head 56 by a plurality of screws 65. A spring contact finger 66 is also secured 100 to said head portion by one of said screws and extends downward and contacts either the insulated portion of the brush carrier when the switch is in "off" position or the conducting brush when the switch is in "on" 105 position. This particular switch, therefore, controls two lights. The center contact 61 is connected with a switch mechanism in a like manner, the switch in connection therewith, however, controlling but one light. 110

The circuit as outlined in the description will now be followed: The current flows from the conductor 25 through any of the switches which may be in "on" position by means of either conductor 32 or 33 through 120 the spring contact fingers of the switch to the respective center contacts, then through the translating devices in contact therewith, through the shell contacts 14, the metal conducting member 13, and out through the 125 conductor 26 secured at 55 to said conducting member.

Assuming that the switch controlling the vertically disposed bulb within the bowl 19 is the only one in "on" position, the circuit 130

would then be from the conductor 25 through binding plate 41, the bracket 40 formed integral therewith, the arm 43, brush 42, spring contact finger 59 and the 5 center contact 58 from where it will pass through the lamp filament to the threaded shell contact 14, the metal conducting member 18, and out through the conductor 26. When the above mentioned switch is in "on" 10 position and the remaining switches are "off," the diffused light is obtained due to the vertically disposed bulb being within the translucent bowl.

Assuming now that the switch controlling 15 two lights is in "on" position, the circuit would then be from the conductor 25 through the binding plate 41, screw 53, conductor bar 32, screw 53^a, through the switch mechanism, spring contact finger 66 and the 20 center contacts 59 and 60, and through whatever translating devices are in contact therewith, through the respective shell contacts and the conducting member 13 out through the conductor 26.

25 The current will pass through corresponding elements in connection with the remaining switch except that an additional conducting bar 33 is disposed between the screws 53^a and 53^b to transmit the current 30 to said last mentioned switch mechanism which controls but one light.

Having thus described my invention what I claim as new and desire to secure by Letters Patent is:

35 1. A stand lamp comprising a pedestal, an insulating base supported at the upper end of said pedestal, receptacle contacts supported by and above said insulating base, a switch mechanism for said contacts also supported by and above said insulating base, 40 a housing above said insulating base for said contacts and switch mechanism, and a pull member for operating said switch extending downwardly through said insulating base.

45 2. A stand lamp comprising a pedestal, an insulating base supported by and above said pedestal, a plurality of lamp receptacles supported by and above said insulating base, 50 a housing for said receptacles, and an indirect lighting bowl supported by and above said housing.

55 3. A stand lamp comprising a pedestal, an insulating base supported at the upper end of said pedestal, said insulating base comprising a raised central portion, and a flange portion surrounding the lower part of said raised central portion, center contacts supported by said raised central portion, switch mechanism for controlling the 60 circuit to said contacts supported on said flange portion, and a housing for enclosing said contacts and switch mechanisms.

65 4. A stand lamp comprising a pedestal having an axial passage therein for the feed

wires, an insulating base supported at the upper end of said pedestal, said insulating base comprising a central portion in the form of an inverted cup and a flange portion surrounding the lower part of said inverted cup-shaped portion, receptacle contacts including center contacts supported by said inverted cup-shaped portion, switch mechanism for controlling the receptacle contacts located on said flange portion, said insulating base having a passage for the feed wires from the inside of said cup-shaped portion to the outside thereof.

5. A stand lamp comprising a pedestal, an insulating base supported thereby, a plurality of center contacts grouped on said insulating base, a plurality of switch mechanisms also grouped on said base, a conducting plate, a plurality of shell contacts thereon, a casing surrounding said insulating base, said center contacts and said conducting plate, said casing being apertured to afford openings for terminals of a plurality of lamps, a plurality of switch mechanisms within said casing and in circuit with said contacts and a lamp bowl supported by said casing, one of said apertures leading thereto, whereby when the lights outside the bowl are off, a diffused light will be obtained from the lamp within the bowl.

6. A stand lamp comprising a pedestal, an insulating base thereon, a conducting plate, a plurality of threaded shell contacts mounted thereon, bushings threaded on said threaded shell contacts, a bowl holder disposed in axial alignment with one of said shell contacts, a casing surrounding said insulating base and supporting said bushings and said bowl holder, and an inverted translucent bowl axially aligned with said bowl holder and the shell contact therein, and means for securing said bowl in said bowl holder.

7. A stand lamp comprising a pedestal, having an axial opening therethrough for the feed wires, an insulating base supported by and above said pedestal, a plurality of lamp receptacles and switch mechanisms supported by and above said insulating base, and a dome-shaped housing above said contacts and switches for housing said insulating base, receptacles and switches, each of said receptacles comprising a center contact and a shell contact, said insulating base having a raised central portion for supporting said center contacts, and an annular flange surrounding said raised portion on which said switch mechanisms are mounted.

8. A stand lamp comprising a pedestal having an axial opening therethrough, a pipe extending through said opening and threaded at its upper end, the passage in the pipe affording a passage for the feed wires, a circular metallic disc threaded on the upper end of said pipe, an insulating base sup-

ported by and above said metallic disc, a plurality of receptacles mounted on said insulating base, a plurality of switch mechanisms mounted on said insulating base, each of said receptacles comprising a center contact and shell contact, said insulating base having a raised central portion for supporting said center contacts, and an annular flange portion surrounding said raised central portion for supporting said switch mechanisms.

9. A stand lamp comprising a pedestal having an axial opening therethrough for the feed wires, an insulating base supported by and above said pedestal, a plurality of lamp receptacles and switch mechanisms supported by and above said insulating base, a dome-shaped housing above said contacts and switches for housing said insulating base, receptacles and switches, each of said receptacles comprising a center contact and a shell contact, said insulating base having a raised central portion for supporting said center contacts, a dome-shaped support surrounding said raised central portion, on which said shell contacts are mounted, and an annular flange surrounding said raised

portion on which said switch mechanisms are mounted.

10. A stand lamp comprising a pedestal having an axial opening therethrough for the feed wires, an insulating base supported by and above said pedestal, a plurality of lamp receptacles and switch mechanisms supported by and above said insulating base, a dome-shaped housing above said contacts and switches for housing said insulating base, receptacles and switches, each of said receptacles comprising a center contact and a shell contact, said insulating base having a raised central portion for supporting said center contacts, a dome-shaped support surrounding said raised central portion, on which said shell contacts are mounted, and an annular flange surrounding said raised portion on which said switch mechanisms are mounted, one of said receptacles being in axial alignment with said pedestal, and an inverted translucent bowl for said axially aligned receptacle, mounted on said housing.

In witness whereof, I have hereunto subscribed my name.

REUBEN B. BENJAMIN.
